UNITED STATES PATENT OFFICE

2,593,346

SAW OPERATING MECHANISM

Willis E. Roe, Chicago, Ill.

Application March 29, 1949, Serial No. 84,098

9 Claims. (Cl. 29—73)

1

This invention relates to certain new and useful improvements in saw operating mechanism particularly constructed and designed to saw rails of a railroad or car track, in or out of track.

A primary object of the invention is to provide a new and improved construction for supporting the saw frame in a horizontal relationship at all times with the rail during the sawing operation and for elevating and holding in a fixed plane the saw blade from the work on the return stroke of the saw frame carrying the saw blade.

Another and equally important object of the invention is to provide a gravity-held saw operating mechanism which can be readily and conveniently clamped over the head of the rail and be firmly held in such position during the sawing operation.

Another object of the invention is to provide a saw operating mechanism which can be operated with the minimum degree of effort and one which can be manufactured at an economical cost.

Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is a side elevational view of the invention showing the same in its relationship to one rail of a train track or car track;

Fig. 2 is a top plan view of the same;

Fig. 3 is a fragmentary sectional detail view taken substantially on line 3—3 of Fig. 1;

Fig. 4 is a fragmentary sectional detail view taken substantially on line 4—4 of Fig. 3;

Fig. 5 is a fragmentary sectional detail view taken substantially on line 5—5 of Fig. 4;

Fig. 6 is a fragmentary sectional detail view taken substantially on line 6—6 of Fig. 1.

The several objects of my invention are best accomplished by the preferred form of construction illustrated in the accompanying drawings, in which drawings a base plate is indicated at 10. This base plate 10 is secured by welding or the like to base flanges 11. These flanges 11 are formed as integral parts of brackets 12 and 13. The brackets 12 and 13 each define at their upper end portion a rounded extension 14. These extensions 14 project between confronting lugs 15 formed as an integral part of the carriage arms 16. These carriage arms 16 are pivotally connected to the brackets 12 by means of nut receiving bolts 17. The upper end portion of

2

these carriage arms 16 is pivotally connected as at 18 to a carriage bar 19. To one end of this carriage bar 19 is connected as at 20 a handle 21 for reasons hereinafter to become apparent. This carriage bar 19 is substantially square in cross section and is provided in its four surfaces with longitudinally extending grooves 21'.

A saw blade carriage comprises a frame 22. This frame 22 comprises an outer or forward depending arm 23 in spaced parallel alignment with respect to an inner or rearward arm 24. The arms 23 and 24 are integrally connected together by a connecting bar 25.

This frame 22 provides at its upper edge portion spaced bearing blocks 26. Slidably projected through these bearing blocks 26 is the carriage bar 19. These bearing blocks 26 have associated therewith anti-friction elements 27 in the form of ball bearings engaging in the grooves 21'. Certain of these ball bearings are maintained in place by retaining bolts 28, Fig. 1.

The lower end portion of the arm 23 has formed therein a horizontal opening 29 into which is slidably mounted a stud shaft 30. One end portion of this stud shaft 30 carries a pin 31. The opposite end portion of the stud shaft is provided with threads 32 and threaded upon this threaded end portion of the shaft 30 is a retaining nut 33.

The arm 24 has formed therein a socket 34 and fixed in this socket in any suitable manner, as by means of a pin 35, is a depending stud shaft 36 having a flattened surface 37 from which projects a pin 38. A saw blade 39 of a standard construction is connected to the frame 22 by engagement with the pins 31 and 38 in a conventional and well-known manner.

By adjusting the tightening or retaining nut 33, the tension of the saw blade 39 may be varied.

The depending arm 24 provides an extension 40 which is adapted to have confronting engagement with the end portion 41 of a connecting link 42. This extension 40 is pivotally connected to the link 42 by means of a nut and bolt assembly 43. The opposite end portion 44 of this link 42 has connection with a slidable block 45 by means of a nut and bolt assembly 46. The opposite end portion 44 of the link 42 is keyed to the bolt 46 by means of a key 47. Mounted on this bolt 46 and keyed thereto by means of the key 47 is a disc 48 bearing cam teeth 49. This disc 48, being keyed to the bolt 46, is movable with the link 42.

The block 45 is mounted for slidable movement 55 in a horizontal plane upon parallelly extending

spaced rods 59. Corresponding end portions 51 of these rods are fixed to the bracket 13 in any approved manner such as, for example, by means of retaining pins 52.

The opposite corresponding end portions 53 of these rods are fixedly secured to a center bracket 54 by means of any approved construction, as by means of pins 55. This center bracket is secured to the base plate 10 by welding or the like.

The block 45 provides lateral extensions 56 and 56' in which the rods 51 are mounted to permit slidable movement of the block 45 relative to these rods. The lower extensions 56' which are arranged in spaced relation with respect to each other, are provided with aligned openings 57 substantially square in cross section. A lifting bar 58 likewise substantially square in cross section is slidably arranged in these openings 57. This lifting bar 58 provides an elevating tooth 59, which is adapted to engage an adjacent tooth 49 of the disc. This lifting bar 58 provides at one end portion a notch 60 and adapted to engage in this notch 60 is a latch head 61 of a slidable bolt 62 carried by the extension 56'. This head 61 operates in an opening 62' formed in the extension 56' and is normally held either against the lifting bar 58 or in the notch 60 by an expansion spring 63. This expansion spring is maintained in the opening 62' upon the bolt 62 by means of a retaining plate 64 secured as at 65 to the extension 56'. The bolt 62 extends through an opening 66 formed in a releasing plate 67. Threaded upon the exterior end portion of this bolt 62 is a retaining nut 68 between which nut and the releasing plate 67 is arranged a washer 69.

The opening 66 in the releasing plate 67 is larger in diameter than the diameter of the bolt 62, to permit pivotal movement of this releasing plate for reasons hereinafter pointed out. This releasing plate is of elongated formation and extends parallel with the adjacent extension 56' in a direction transversely with respect to the movement of the carriage block 45 upon the rods 50. It is pivotally connected to the block 45 by a bolt 70, the shank of which extends through an opening 70' which is of a diameter greater than the diameter of the shank of the bolt 70.

The intermediate bracket 54 carries a pin 71 having a conically tapered end portion 72. This pin 71 is disposed in alignment with respect to the space 73 (Fig. 5) between the releasing plate 67 and the adjacent extension 56'.

When the latch head 61 is disengaged from the notch 60 in a manner to be presently explained, the end portion 74 of the lifting bar 58 normally extends beyond the adjacent extension 56' to a position indicated in dotted lines A (Fig. 4) and as shown in Fig. 1.

The brackets 12 and 13 and the bracket 54 each provide a laterally extending supporting arm 75. Secured to these arms 75 and fixed thereto by means of bolts 76 is a tie plate 77, for the purpose of tying brackets 12, 13, and 54 together to give rigidity.

The bracket 12 on one side thereof provides a lateral frame 78, the vertical wall 79 thereof being provided with an elongated slot 80. Adjustably secured to this frame 78 by means of bolts 81 which are mounted in the slot 80, is a clamping jaw 82. This clamping jaw 82 is provided with spaced aligned openings 83 for the projection therethrough of guide rods 84.

Between these openings 83 is a tapped opening 85 into which is threaded an adjusting bolt 86.

The outer corresponding end portions of the guide rods 84 are fixed in sockets 87 of a complementary clamping jaw 88. The threaded shank 86 has an enlarged portion 89, and carried by this portion 89 is a handle 90 by which the threaded shank 86 may be rotated to adjust the clamping jaws 82 and 88 relative to each other and for clamping these jaws upon the head 91 of a rail 92 to be sawed.

10 The enlarged portion 89 is provided with a circular groove 92' and engaging in this groove 92' is a pin 93 which restrains the movement of the jaw relative to the enlarged portion 89, while permitting rotation of this portion relative thereto.

The tie plate 77 is preferably channel-shaped in cross section for strengthening purposes.

The saw blade 39 bears upon the head 91 of the rail 92 by virtue of the weight of the carriage frame 22 and in this respect the saw blade is gravity fed.

20 Pivotally connected as at 94 is a handle socket 95, mounted in the tapered socket 96 of which is a handle 97. This handle socket 95 is pivotally connected to the block 45 by means of a connecting link 98 carried by the bolt assembly 46 and connected to the handle socket by a bolt 99.

In operation the device is positioned with respect to the rail 92 in the manner shown in Fig. 2, with the rail head 91 firmly clamped between the jaws 82 and 88.

The sawing takes effect upon the back stroke. When the frame is in its extreme rear position, such as shown in Fig. 1, the end portion 74 of the lifting bar 58 will strike the bracket 13. This engagement of the lifting bar 58 with the bracket 13 will move the bar 58 relative to the block 45 and, in so doing, the tooth 59 of the lifting bar will engage the adjacent tooth 49 of the disc 48 and rotate that disc 48 in an anticlockwise direction. This disc 48 being keyed to the bolt 46 and the bolt 46 being keyed to the connecting link 42, will rotate the connecting link in an anticlockwise direction. As this link 42 is fixedly secured to the carriage frame 22, this rotation of the link 42 in anticlockwise direction will elevate the carriage frame 22 to disengage the saw blade 39 from the rail head 91 during the forward movement of the carriage frame 22, which forward movement is brought about by pivoting the socket handle 95 in a forward direction.

55 The forward movement of the lifting bar 58 by engagement with the bracket 13 will move the notch 60 in a position to receive the latch head 61 so as to latch this lifting bar to the block 45 during this lifting operation of the frame 22.

60 When the frame 22 has reached its extreme forward position, the pin 71 will engage between the release bar 67 and the adjacent projection or extension 56' whereby to disengage the latch head 61 from the notch 60, whereupon the lifting bar 58 will, by reason of the weight of the frame on the link 42, be pivoted to its rearmost position as the saw blade 39 moves by gravity upon the rail head 91 and serves to saw the rail during the back stroke of the frame 22. In this manner the blade 39 in the forward stroke of the frame is elevated from engagement with the rail head 91 and is automatically dropped into sawing operation at the beginning of the back stroke of the frame 22.

75 By actuating the handle 97 in a backward and

forward motion, the operator may with ease reciprocate the saw frame relative to the carriage bar 19 to perform the sawing operation.

When it is desirable to remove the device from the rail to permit the passage of a train or for any other reason, the operator by manipulation of the handle 97 in a full backward direction causing the lifting bar 58 to become locked to block 45 by means of latch head 61 engaging notch 60, which holds frame 22 in a fixed vertical plane, and then, by grasping the handle 21, and exerting pressure backwards, he may pivot the saw blade 39 to its extreme vertical position and out of engagement with the rail head 91 for quick removal of the device from engagement with the rail, after turning clamp handle 90 counterclockwise to release clamp 87 from rail head 91, allowing device to be removed.

The present invention constitutes an improvement over that shown and described in United States Letters Patent No. 1,900,304.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A rail saw comprising a base plate, spaced supporting brackets on said plate, a carriage bar extending above and in parallel relation on all planes within the scope of vertical travel with respect to said base plate, link connections between said brackets and said carriage bar whereby said carriage bar may be moved relative to said base plate, a carriage frame, means providing slidable connection between the carriage frame and the carriage bar, a saw blade carried by said frame, an intermediate bracket carried by said base plate in parallel spaced relation with respect to said first-named brackets, a bearing block, guide rods carried between the intermediate bracket and one of said first-named brackets and having operative slidable connection with said bearing block, a link connection between said bearing block and said carriage frame, a handle bearing socket pivotally connected to said one of said brackets, a link connection between said handle and said bearing block for reciprocating said bearing block relative to said guide rods and said frame relative to said carriage bar.

2. A rail saw comprising a base plate, spaced supporting brackets on said plate, a carriage bar extending above and in parallel relation on all planes within its scope of vertical travel with respect to said base plate, link connections between said brackets and said carriage bar whereby said carriage bar may be moved relative to said base plate, a carriage frame, means providing slidable connection between the carriage frame and the carriage bar, a saw blade carried by said frame, an intermediate bracket carried by said base plate in parallel spaced relation with respect to said first-named brackets, a bearing block, guide rods carried between the intermediate bracket and one of said first-named brackets and having operative slidable connection with said bearing block, a link connection between said bearing block and said carriage frame, a handle bearing socket pivotally connected to said one

of said brackets, a link connection between said handle and said bearing block for reciprocating said bearing block relative to said guide rods and said frame relative to said carriage bar, and means for clampingly connecting said base plate to the head of a track rail.

3. A rail saw comprising a base plate, spaced supporting brackets on said plate, a carriage bar extending above and in parallel relation on all planes within its scope of vertical travel with respect to said base plate, link connections between said brackets and said carriage bar whereby said carriage bar may be moved relative to said base plate, a carriage frame, means providing slidable connection between the carriage frame and the carriage bar, a saw blade carried by said frame, an intermediate bracket carried by said base plate in parallel spaced relation with respect to said first-named brackets, a bearing block, guide rods carried between the intermediate bracket and one of said first-named brackets and having operative slidable connection with said bearing block, a link connection between said bearing block and said carriage frame, a handle bearing socket pivotally connected to said one of said brackets, a link connection between said handle and said bearing block for reciprocating said bearing block relative to said guide rods and said frame relative to said carriage bar, means for elevating said carriage bar and said frame at the completion of the back stroke of said bearing block, means for latching said carriage bar and said frame in said elevated position during the forward stroke of said bearing block with respect to said guide rods, and means for releasing said latching means to permit said frame and said carriage bar to deposit said blade upon the head of a track rail.

4. A rail saw comprising a base plate, spaced supporting brackets on said plate, a carriage bar extending above and in parallel relation on all planes within its scope of vertical travel with respect to said base plate, link connections between said brackets and said carriage bar whereby said carriage bar may be moved relative to said base plate, a carriage frame, means providing slidable connection between the carriage frame and the carriage bar, a saw blade carried by said frame, an intermediate bracket carried by said base plate in parallel spaced relation with respect to said first-named brackets, a bearing block, guide rods carried between the intermediate bracket and one of said first-named brackets and having operative slidable connection with said bearing block, a link connection between said bearing block and said carriage frame, a handle bearing socket pivotally connected to said one of said brackets, a link connection between said handle and said bearing block for reciprocating said bearing block relative to said guide rods and said frame relative to said carriage bar, means for clampingly connecting said base plate to the head of a track rail, means for elevating said carriage bar and said frame at the completion of the back stroke of said bearing block, means for latching said carriage bar and said frame in said elevated position during the forward stroke of said bearing block with respect to said guide rods, and means for releasing said latching means to permit said frame and said carriage bar to deposit said blade upon said rail head.

5. A rail saw comprising a base plate, spaced supporting brackets on said plate, a carriage bar extending above and in parallel relation with respect to said base plate, link connections between

said brackets and said carriage bar whereby said carriage bar may be moved relative to said base plate, a carriage frame, means providing slidable connection between the carriage frame and the carriage bar, a saw blade carried by said frame, an intermediate bracket carried by said base plate in parallel spaced relation with respect to said first-named brackets, a bearing block, guide rods carried between the intermediate bracket and one of said first-named brackets and having operative slidable connection with said bearing block, a link connection between said bearing block and said carriage frame, a handle bearing socket pivotally connected to said one of said brackets, a link connection between said handle and said bearing block for reciprocating said bearing block relative to said guide rods and said frame relative to said carriage bar, and a channel plate carried by said brackets in longitudinal spaced relation with respect to and above said base plate.

6. A rail saw comprising a base plate, spaced supporting brackets on said plate, a carriage bar extending above and in parallel relation on all planes within its scope of vertical travel with respect to said base plate, link connections between said brackets and said carriage bar whereby said carriage bar may be moved relative to said base plate, a carriage frame, means providing slidable connection between the carriage frame and the carriage bar, a saw blade carried by said frame, an intermediate bracket carried by said base plate in parallel spaced relation with respect to said first-named brackets, a bearing block, guide rods carried between the intermediate bracket and one of said first-named brackets and having operative slidable connection with said bearing block, a link connection between said bearing block and said carriage frame, a handle bearing socket pivotally connected to said one of said brackets, a link connection between said handle and said bearing block for reciprocating said bearing block relative to said guide rods and said frame relative to said carriage bar, means for clampingly connecting said base plate to the head of a track rail, and a channel plate carried by said brackets in longitudinal spaced relation with respect to and above said base plate.

7. A rail saw comprising a base plate, spaced supporting brackets on said plate, a carriage bar extending above and in parallel relation on all planes within its scope of vertical travel with respect to said base plate, link connections between said brackets and said carriage bar whereby said carriage bar may be moved relative to said base plate, a carriage frame, means providing slidable connection between the carriage frame and the carriage bar, a saw blade carried by said frame, an intermediate bracket carried by said base plate in parallel spaced relation with respect to said first-named brackets, a bearing block, guide rods carried between the intermediate bracket and one of said first-named brackets and having operative slidable connection with said bearing block, a link connection between said bearing block and said carriage frame, a handle bearing socket pivotally connected to said one of said brackets, a link connection between

said handle and said bearing block for reciprocating said bearing block relative to said guide rods and said frame relative to said carriage bar, means for elevating said carriage bar and said frame at the completion of the back stroke of said bearing block, means for latching said carriage bar and said frame in said elevated position during the forward stroke of said bearing block with respect to said guide rods, means for releasing said latching means to permit said frame and said carriage bar to deposit said blade upon the head of a track rail, and a channel plate carried by said brackets in longitudinal spaced relation with respect to and above said base plate.

5 8. For a combination comprising a pair of supporting brackets, guide rods carried by and extending between said brackets, a bearing block slidably mounted on said guide rods, a saw carriage frame pivotally supported from said bearing block, means for elevating said carriage frame when said block reaches the end of its 10 slidable movement in one direction with respect to said guide rods, means for latching said carriage frame when said block reaches the end of its 15 slidable movement in one direction with respect to said guide rods, means for latching said carriage frame in said elevated position during movement of the bearing block in an opposite direction with respect to said guide rods, and 20 means for disengaging said latching means when said block reaches the end of its slidable movement in said opposite direction to permit said 25 saw carriage frame to move by gravity to dispose a saw blade carried thereby upon the head of a 30 track rail.

9. For a combination comprising a pair of supporting brackets, guide rods carried by and extending between said brackets, a bearing block slidably mounted on said guide rods, a saw carriage frame pivotally supported from said bearing block, means for elevating said carriage frame when said block reaches the end of its 35 slidable movement in one direction with respect to said guide rods, means for latching said carriage frame when said block reaches the end of its 40 slidable movement in one direction with respect to said guide rods, means for latching said carriage frame in said elevated position during movement of the bearing block in an opposite 45 direction with respect to said guide rods, means for disengaging said latching means when said 50 block reaches the end of its slidable movement in said opposite direction to permit said saw carriage frame to move by gravity to dispose a 55 saw blade carried thereby upon the head of a track rail, and means for clampingly positioning said saw carriage frame with respect to said rail.
